(57) CLAIM

The ornamental design for a jeans bag, as shown and described.

DESCRIPTION

FIG. 1 is a perspective view of the jeans bag showing our new design;

FIG. 2 is a front elevation view thereof;

FIG. 3 is a back elevation view thereof;

FIG. 4 is a right side elevation view, which is identical to the left side elevation view thereof;

FIG. 5 is a top plan view thereof; and,

FIG. 6 is a bottom plan view thereof.

The broken lines shown in the drawings represent stitching.
